UNITED STATES PATENT OFFICE.

INGEMAR RYSTEDT AND MELVIN STEELE, OF DAYTON, OHIO.

FLYING-MACHINE.

1,075,863.

Specification of Letters Patent. Patented Oct. 14, 1913.

Application filed August 31, 1912. Serial No. 718,086.

To all whom it may concern:

Be it known that we, INGEMAR RYSTEDT and MELVIN STEELE, citizens of the United States, residing at Dayton, in the county of Montgomery and State of Ohio, have invented new and useful Improvements in Flying-Machines, of which the following is a specification.

This invention is an improved flying machine and consists in the construction, combination and arrangement of devices herein-after described and claimed.

The object of our invention is to provide a flying machine which may be also operated in the water.

Another object is to provide a machine of this class with novel lifting propellers of improved construction.

Another object is to effect improvements in the construction of the body of the machine.

Another object is to provide the machine with improved safety devices to prevent the machine from falling in the event of an accident.

Another object is to effect improvements in the arrangement of the motors and the power transmission mechanisms whereby the motors may be employed separately or simultaneously and whereby the power of both of them may be concentrated either on the driving propeller or the lifting propellers as may be required.

Another object is to effect improvements in the construction of the vertical rudder.

In the accompanying drawings:—Figure 1 is a perspective view of a flying machine constructed in accordance with our invention. Fig. 2 is a similar view, showing the platform, the supporting frame therefor, the motors, the controlling mechanisms and the driving propeller. Fig. 3 is a vertical transverse sectional view on the plane indicated by the line *a—a* of Fig. 1. Figs. 4, 5 and 6 are detail views.

The body of our improved flying machine is hollow and is substantially in the form of a torpedo with a round bottom 2, pointed ends 3 and a dome-shaped top 4. At the front and rear ends of the body are observation openings 5 which are provided with glass panes 6. On the outer side of the body at opposite sides thereof are longitudinally arranged tanks 7—8 one for gasoline wherewith to operate the engines and the

other for lubricating oil. On the dome-shaped top, at opposite sides thereof, are substantially semi-tubular casings 9, the inner sides of which are here shown as also forming the top of the body as at 10. Suitable braces 11 connect the sides of the body to the outer sides of the said semi-tubular casings and serve to brace and strengthen the body and also the said casings. A supporting frame 12 is arranged below the body 60 and is connected thereto by means of braces 13 at the front and rear ends. This supporting frame is provided with four supporting wheels 14 which permit the machine to run on the ground.

A frame 15 projects from the rear end of the machine and comprises an upper bar 16, and also a bar 17 and a vertical end bar 18. The upper and lower bars are provided with vertical offset portions 19 to clear the blades 75 of the driving propeller 20. The propeller shaft 21 is mounted in bearings in hangers 22 which depend from a longitudinally arranged supporting beam 23 which is secured in the body 1 and extends nearly from end 80 to end thereof. A motor carrying platform 24 has its ends connected to the ends of the beam 23 by means of inclined downwardly diverging pairs of hanger bars 25 and at the center of the said platform, at one side thereof, is a gang plank or extension 26 which leads from an opening 27 in one side of the body of the machine, which opening has a door 28 for closing the same.

Substantially triangular frames 29 are 90 connected to the platform 24 with their upper portion arranged above the body, the horizontal upper bars 30 of the said frames being arranged on the ridge of the top of the body and the inclined side bars 31 of the 95 said frames extending down through the top of the body, as shown in detail in Fig. 3. In the upper corners of the said frames are bearings 32 in which are journaled the axle shafts 33 of two pairs of lifting propellers 100 34, one pair of the said propellers being arranged above each of the semi-tubular casings 9 coaxially with the said semi-tubular casings. Each of the said lifting propellers comprises a pair of oppositely arranged, longitudinal blades 35 which are tangent to a circle concentric with the said propellers, and spoke arms 36, which connect the front and rear sides of the said blades of the axle shafts. A dead air drum 37 is loosely 110

mounted on the axle shaft of each lifting propeller. Each of these dead air drums is of substantially semi-cylindrical form and hangs from the propeller shaft with its lower side coaxial with and spaced from the associated semi-tubular casing 9.

Each lifting propeller shaft has a sprocket wheel 38. The driving propeller shaft has a sprocket wheel 39. A pair of motors 40-41 which may be of any suitable type are mounted on the platform 24, the motor 40 in front and the motor 41 to the rear. The respective power shafts 42-43 of the said motors are in line with each other, the shaft 42 being provided with a pair of sprocket wheels 44 and the shaft 43 having a sliding clutch element 45. A sleeve 46 is loose on the shaft 43 and is provided with a sprocket wheel 47 and also with a clutch element 48 so that when the said clutch element 48 is engaged by the clutch element 45 the said sprocket wheel 47 is caused to turn with the shaft 43. An endless sprocket chain 49 connects the sprocket wheel 47 and the sprocket wheel 39 of the driving propeller shaft. Endless sprocket chains 50 connect the sprocket wheels 44 of the motor shaft 42 with the sprocket wheels 38 of the lifting propeller shafts and one of these endless sprocket chains is crossed and has its crossed portions guided through tubes 51. Hence, the lifting propellers when driven by the motor shaft 42 are revolved in reverse directions. On the rear end of the motor shaft 42 is a clutch element 52. On the front end of the motor shaft 43 is a sleeve 53 splined thereto for longitudinal movement and also for rotation therewith and this sleeve is provided at its front end with a clutch element 54 which may be engaged with the clutch element 52 to lock the two motor shafts together and cause them to rotate in unison and thus enable the power of both motors or engines to be employed for operating the lifting propellers. When the clutch element 54 is disconnected from the clutch element 52 as is usual, the lifting propellers will be driven by the motor 40 and the driving propeller by the motor 41.

When it is desired to couple both the motors together and cause them to coact in operating the lifting propellers, the clutch element 45 is disengaged from the clutch element 48, thereby throwing the driving propeller out of gear and the clutch element 54 is engaged with the clutch element 52. To thus operate the movable clutch elements, we provide a shifter 55 which is connected to the sleeve 53 and is pivoted at 56 and also provide a shifter 57 which is connected to the sleeve of the clutch element 45 and is pivoted at 58. The free end of the shifter 55 is reduced and engaged with a slot 59 in a lever 60. The free end of the shifter 57

is also reduced and engaged with the slot 61 of a rock arm 62, this rock arm being connected by a rod 63 to the lever 60 so that when the said lever is operated by the aviator, both the clutches are simultaneously operated, as will be understood. The said lever 60 may be locked in either position to a segment rack 64 by means of a rocking dog 65 of the usual construction with which the said lever is provided. The seat for the aviator is convenient to the lever 60 and is indicated at 66. The vertical rudder 67 comprises an oblong quadrangular open frame 68 pivotally mounted as at 69 in the rear portion of the frame 15 and provided on its four sides with adjustable planes 70 each of which is connected at its rear end to a spring roller 71 and adapted to be rolled thereon. Hence, by unrolling the said planes from their spring rollers the effective area of the said planes may be varied as may be required. The frame 67 may be turned as required, in a horizontal plane, in order to steer the machine, by steering ropes 72 which are attached to the said frame as at 73 and are led forward and engaged with suitable direction pulleys 74 which are mounted on the platform 24, the said steering ropes being connected to and operated by a steering wheel 75. The steering wheel is mounted on a suitable standard 76 which is arranged in front of the seat 66.

Adjusting cords 77 for the planes 70 of the vertical rudder are attached to the said planes at the free ends of the latter, engaged with suitable direction pulleys 78 with which the frame 67 is provided, run forward and connected to a cord 79 which engages direction elements 80 mounted on and under the beam 23 and the front end of this cord 79 is attached to a winch 81 for winding on the latter, the winch being mounted in a frame 82 which depends from the beam 23 and being provided with a pinion 83. A vertically movable rack bar 84 engages the pinion and operates in guides 85 with which the frame 82 is provided. An adjusting lever 86 for operating the said rack bar is connected to the latter by a pin 87 which operates in a slot 88 with which said adjustable lever is provided, the said adjustable lever being fulcrumed as at 89 and being arranged conveniently to the seat 66. Hence, the aviator by moving the free end of the lever upwardly or downwardly as required may cause the rack bar and pinion to coöperate to turn the winch so as to let out or wind up the adjusting cord 79 and, hence, cause the adjustable steering planes 70 to be unrolled to any desired extent.

A horizontal rudder 90 is pivotally mounted at the rear end of the frame 15, as at 91 and is operated by cords 92 which cords are run forward and engaged with

certain direction pulleys 93 mounted on the platform 24, the front ends of the said cords being attached to a tiller 95 which is mounted on a support 96 in front of the seat 66. This tiller may be operated by the feet of the aviator and also forms a foot rest.

The body of our improved flying machine is provided with a pair of longitudinally arranged substantially semi-tubular safety wings 96 which are pivotally connected to opposite sides of the body as at 97 and are adapted to be folded under the body of the flying machine and arranged in concentric relation to each other. Springs 98 are connected to these safety wings to turn the latter on their pivots and spread them from opposite sides of the body of the machine, as indicated in dotted lines in Fig. 3. Normally the said safety wings are held in closed position by means of catches 99. Cords 100 are attached to these catches and connected to an operating cord 101 which engages suitable direction pulleys 102 and is connected to the controlling lever 60. Hence, when the controlling lever is operated to throw the driving propeller out of gear and couple the two motors together, so as to apply all of their power to the lifting propellers, the controlling lever also pulls the cords 100 and 101 and, hence, causes the catches to release the safety wings and, thereupon the latter are spread from opposite sides of the machine and serve to buoy the same in the air and prevent the machine from falling. These safety wings act as parachutes and each is provided at the center with a spill opening 103.

In order to enable the machine to be steered when the same is operating in the water, a rudder 104 is provided which is pivotally connected to the under side of the frame 15 at a point in rear of the driving propeller 20. The tiller or yoke 105 of this rudder is connected by cords 106 to a parallel pivoted bar 107 and tiller ropes 108 are connected to this bar and run forward and are engaged with direction pulleys 108 with which the machine is provided, the extreme front ends of the said tiller ropes hanging just in front of the seat 66 and being provided with suitable handles 109 to enable them to be readily pulled in order to turn the rudder and, hence, to steer the machine in water. A shaft 110 is also provided for opening valves 111 for relieving

compression of the cylinders of the engine 40.

While we have herein shown and described a preferred form of our invention, we would have it understood that changes may be made in the form, proportion and construction of the several parts without departing from the spirit of our invention and within the scope of the appended claims.

We claim:—

1. In combination with the frame or body of a flying machine, safety wings pivotally connected to opposite sides of the frame or body and adapted to be folded in overlapped relation under the frame or body, and means to turn the safety wings and cause them to be spread and extended from opposite sides of the frame or body. 75

2. In a flying machine, a frame or body having substantially semi-tubular casings at opposite sides and lifting propellers mounted above the said casings and provided with horizontal axes and with tangential blades, the planes of rotation of said lifting propellers being substantially concentric with the semi-tubular casings. 30

3. In a flying machine, a frame or body having substantially semi-tubular casings at opposite sides, lifting propellers above the said casings and provided with horizontal axes and with tangential blades, the paths of rotation of said lifting propellers being substantially concentric with the said semi-tubular casings, and dead air drums arranged on the axes of the lifting propellers and around which the latter revolve. 90

4. A flying machine of the class described having lifting propellers, a motor to operate the lifting propellers, a driving propeller, a motor to operate the driving propeller, parachute wings, devices to release the parachute wings, couplings to simultaneously throw the driving propeller out of gear and connect the shafts of the two motors together, and operating means for the said couplings, the said operating means being also connected to the parachute wing releasing devices. 100 100
